A. A. KRAMER.
SHEET METAL BUILDING.
APPLICATION FILED MAR. 3, 1916.

1,229,477.

Patented June 12, 1917.

UNITED STATES PATENT OFFICE.

ANDREW A. KRAMER, OF KANSAS CITY, KANSAS.

SHEET-METAL BUILDING.

1,229,477.

Specification of Letters Patent. Patented June 12, 1917.

Application filed March 8, 1916. Serial No. 81,835.

To all whom it may concern:

Be it known that I, ANDREW A. KRAMER, a citizen of the United States, residing at Kansas City, in the county of Wyandotte 5 and State of Kansas, have invented certain new and useful Improvements in Sheet-Metal Buildings; and I do declare the following to be a full, clear, and exact description of the invention, such as will enable 10 others skilled in the art to which it appertains to make and use the same, reference being had to the accompanying drawings, and to the letters and figures of reference marked thereon, which form a part of this 15 specification.

My invention relates to sheet metal buildings, and more particularly to a structure of that character adaptable for use as a garage or shed for housing implements or 20 vehicles, the principal object of the invention being to provide a structure which may be built up in sections, and that may be combined in a manner to render the structure weather proof and of substantial rigidity.

It is also an object of the invention to provide a structure of this character which is stiffened by what I term "box joints" which not only afford reinforcing and stiffening elements to the structure but also afford 30 means for securely connecting the sections of which the building is formed in a manner to seal the joints against wind and rain.

It is also an object of the invention to provide a box joint structure which may be 35 bent at the corners of the building and ridge of the roof without splitting or breaking the box rib.

In accomplishing these and other objects of the invention I have provided improved 40 details of structure, the preferred forms of which are illustrated in the accompanying drawings, wherein:

Figure 1 is a perspective view of a sheet metal building constructed according to my 45 invention, indicating the placement of one of the sections.

Fig. 2 is a horizontal section on the line 2—2 Fig. 1.

Fig. 3 is an enlarged interior perspective 50 of a part of one end of the building.

Fig. 4 is a similar view of part of the rear of the building.

Fig. 5 is a detail perspective view of a roof section.

Fig. 6 is an enlarged detail perspective view 55 of part of a roof section, particularly illustrating a box rib at the ridge of the roof.

Fig. 7 is a horizontal section on the line 7—7 Fig. 1, illustrating a box joint.

Referring more in detail to the drawings:

I designates the building as a whole, which comprises the sides 1, roof 2, closed rear end 4, hinged front doors 5—6, the front roof panel 7, and the windows 8, all of which, 65 except the windows, are constructed of sheet metal and combined to form a building structure. The said wall members are made up of separate sections of say thirty inch width, and provided with box ribs 9, which 70 may be formed in a press or brake and comprise outstanding ribs, preferably square in cross section and all of the same dimensions so that a rib in one section may spread over a rib in another section to form a joint, a 75 rib being arranged along each longitudinal edge of each strip so that joints may be formed at the meeting edges of the strips.

The roof is also formed in sections of the same width as the side sections, and has ribs 80 11 corresponding to ribs 9 in the side sections, so that they may nest thereover to form joints in the same manner as the joints are formed along the side walls, the roof sections being arched at the center and 85 curved at the edges to turn downwardly and form extensions of the upper portions of the side wall sections, the overlap portions of the side wall and roof sections being connected by bolts or the like 13 which extend 90 through the overlapped parts in order to form a substantial and integral structure.

In order to stiffen the wall and roof sections I preferably corrugate the same transversely, as illustrated in Figs. 3 to 6 inclusive, the corrugations not only serving to form a rigid structure, but also making it possible to bend the sections so that the ridge and edge turns may be made on the roof sections, it being apparent that the 100 presence of the box rib would render it difficult to effect the bend without some means of expansion being provided, and it being further apparent that with the sections or strips of metal being corrugated transversely, prior to the formation of the rib, when the sheet is bent after the ribs and corrugation are in, the extra metal provided by the corrugation will enable the ribs to straighten out by taking up such surplus 105 and thereby effect the bend, the metal at the bends being substantially smooth or minus the corrugations after the bending operation (Figs. 5 and 6).

The back of the building is preferably formed of continuous vertical strips of the corrugated and box ribbed metal, so that there is no break between the roof and the ground, but at the front of the building I preferably provide the panel 7 that closes the structure above the door line. In this way it is possible to provide simple doors of rectangular shape, having a combined width substantially equal to the width of the building, so that their outer edges may be hinged to the side walls while their inner edges may meet at the center of the door opening.

15 The doors are preferably hinged to narrow panels 14, having backturned flanges 14' bolted to adjacent side wall strips and preferably have box ribs 9' nesting over the end ribs 9 of said strips and extended a short distance along the side walls.

In order to further simplify the construction so that an additional piece for forming a stop for the upper edges of the doors may be unnecessary, I turn the lower edge of the roof panel 7 outwardly at the upper door line and backwardly to form the double flange 15, the rear edge of the under ply of which is turned down and then upwardly to form a double thickness stop rail 16, against which the upper edges of the door members 5—6 may abut. In order to stiffen the panel and the stop rail I attach triangular corner pieces 18 to the panel and adjacent side walls by bolts 19, each corner piece comprising a body part and upturned edge flanges 20 through which latter the bolts 19 are projected.

In order to further stiffen the building and protect the same I provide the seat 22 for the side walls, which preferably consists of angle iron to which the lower edges of the wall sections may be secured by bolts 23, and above the seat members I attach channel irons 24 to the said side wall sections in order to stiffen the walls at intermediate points, the channels preferably running entirely about the building and at the inside thereof and further forming supports for a shelf 25 at the rear of the building.

50 Windows of any suitable type may be provided, those illustrated herein comprising circular openings 27 equipped with the glass panes 28 that may be pivotally mounted to swing inwardly and outwardly within the opening.

In manufacturing the building, the sheet metal strips, of proper width and length, are first run through a corrugating machine to form the transverse corrugations. They are then worked in a brake or press to form the longitudinal box ribs. The roof sections are then shaped on a suitable form, the

transverse corrugations in the roof sheet strip enabling the metal to be bent on the form, as the surplus material formed by the corrugations will enable the metal to expand in order to form the curve and being particularly advantageous in the formation of the curve over the box rib, as the metal may expand and straighten out the corrugations gradually in order that the metal may turn to the proper shape.

When the building is to be erected, two side wall sections are connected with one roof section to form a unit, as illustrated in Fig. 1, and the said sections are bolted or riveted together in order to form the integral structure. When the units are formed they may be erected so that the box joints overlap and may be bolted together, each section being arranged and connected successively until the building has reached the desired length. The end strips may then be applied to one end of the building and the roof panel to the other, and the interior stiffening channels and the base seat connected with the side walls as before described.

The doors are then hung, with the hinges at the front ends of the side wall sections and the windows installed.

It is apparent that a building of this construction may be manufactured and erected at small cost and will afford a substantial structure within which to house vehicles or implements. It is apparent that by suitably coating the metal its life may be prolonged indefinitely and that the shelter can be taken down to be moved in sections if desired.

Having thus described my invention, what I claim as new therein, and desire to secure by Letters-Patent, is:—

1. A building comprising side wall and roof members, each composed of initially independent strips of sheet metal, corrugated transversely and box ribbed longitudinally, the roof sections being bent to form a ridge through the body portions and box ribs, and the box ribs on the roof nesting with the box ribs on the side wall sections.

2. A sheet metal structure comprising side wall and roof sections, made of initially independent sheets of metal, corrugated transversely and box ribbed longitudinally, the roof strips being bent to form ridge and edge portions, the side wall and roof strips having box ribs along their longitudinal edges, with the edge ribs on one section nesting with like ribs on an adjacent section and with the ribs of the roof strip nested with ribs of the side wall sections.

In testimony whereof I affix my signature.

ANDREW A. KRAMER.
